UNITED STATES PATENT OFFICE.

TATSUJIRO IMAIZUMI, OF SEATTLE, WASHINGTON.

CANTEEN-FILTER.

1,308,242.

Specification of Letters Patent.

Patented July 1, 1919.

Application filed November 6, 1918. Serial No. 261,356.

To all whom it may concern:

Be it known that I, TATSUJIRO IMAIZUMI, a subject of the Emperor of Japan, and resident of the city of Seattle, county of King, 5 and State of Washington, have invented certain new and useful Improvements in Canteen - Filters, of which the following is a specification.

My invention relates to filters desired for 10 use in connection with a canteen, or other like container.

The object of my invention is to provide a filtering apparatus which may be applied to a canteen, or other like container, which, in 15 addition to filtering the water as it is drunk, provides means for more conveniently using the canteen to drink from.

My invention comprises the novel parts and combinations of parts which will be described, and then specifically pointed out in 20 the claims.

In the accompanying drawings I have 25 shown my invention, embodied in the form of construction which is now preferred by me.

Figure 1 shows a canteen in section, having my filter therein, the cap of the canteen being in place.

Fig. 2 shows, in perspective and in longitudinal section, the filter mechanism.

Fig. 3 shows my filtering and drink attachment removed from the container.

Canteens are usually provided with a comparatively large neck and mouth and, 35 for this reason, are inconvenient to drink from. By my invention I provide a means which may be employed for filtering the water so as to remove from it dangerous germs and at the same time means whereby 40 drinking from the canteen may be made more convenient. The device is also of such construction that it may be placed entirely within the canteen out of sight when not in use.

I provide a base member A, which, as 45 herein shown, is in the form of a sleeve having a diaphragm extending across it, said sleeve being of a size to fit within the neck P of the canteen. This sleeve is preferably

50 provided with a flange B at its upper end which extends outward far enough to bear upon the outer end face of the canteen neck.

The cap R of the canteen fits over this 55 flange B and when screwed down into place forces the flange down upon the end face of

the canteen neck. To insure a tight joint I employ a rubber ring D of a packing member beneath the flange B and engaging the outer end face of the canteen neck.

It is evident that this base member may 60 be made of other form. The result desired is a base member which will enter the canteen neck and be held therein by the canteen cap.

Within and supported from this base, so 65 that it may have endwise reciprocation, is a tube F which forms a mouth piece and through which water is drawn. As herein shown, the base piece A has a diaphragm E located a short distance inward from its outer end which has a hole of such a size to permit free passage of the mouth piece tube F. The outer end of this mouth piece tube is provided with a flange S which will prevent its being pushed through the dia- 70 phragm E from the outside.

The filter is secured to the inner end of the tube F and, as herein shown, consists of a cup-like member K and a cap G, these being shown as screw-threaded together. To 80 the opposite or lower side of the filter is a nipple N to which is secured a draft tube O, the latter being of flexible rubber. The cap G of the filter has its upper surface preferably extending across the lower end of the 85 tube F and provided with a few small holes I. The chamber formed by the cup K is filled with a small amount of cotton or any desired filtering material.

The base member A and the filter member 90 are connected by a spring J which is so formed that its tendency is to raise the filter relative to the cap, that is, so as to project the outer end of the mouth piece tube F, as is shown in Figs. 2 and 3. In this position 95 it may be taken in the mouth and water readily drawn.

Fitting of the tube within the hole in the diaphragm E is sufficiently loose to permit air to enter the canteen to replace the water 100 drawn out. By this device it is possible to drink from the canteen with greater ease and more comfort than from such a large opening as the neck P.

When the canteen is to be closed, the tube 105 is pushed in by the cap R and when the cap is screwed down, the packing ring D makes a tight joint with the outer face of the neck P, while the disk T inside of the canteen cap makes a tight joint with the end of the tube 110

F. When the canteen cap is removed, the spring J will project the mouth piece tube F.

What I claim as my invention is:

1. A drinking device for canteens comprising a suction tube, a base piece fitting within the canteen mouth and through which the mouthpiece of the tube may project, and a spring connecting said base piece and tube and acting to project the mouth piece.
- 10 2. A drinking device for canteens comprising a base adapted to fit within the canteen mouth, a tube forming a mouthpiece and having guiding support from said base, a spring connecting said base and tube and acting to project the tube, and a flexible tube extending from the mouthpiece tube.
- 20 3. A drinking device for canteens comprising a base adapted to fit within the canteen mouth, a tube forming a mouthpiece and having guiding support from said base, a spring connecting said base and tube and acting to project the tube, a strainer secured to the inner end of the mouthpiece tube, and a draft tube extending from said strainer.
- 25 4. A drinking device for canteens comprising a base adapted to be secured in the canteen neck by the usual canteen cap, a mouthpiece tube supported from said base to be projected from and withdrawn into the can-

teen neck, a filter secured to said tube and through which the water is drawn, a draft tube extending from the filter, and a spring surrounding the mouthpiece tube between the base and filter and acting to project the mouthpiece when the canteen cap is removed.

5. A drinking device for canteens comprising a mouthpiece tube, a tube-like base adapted to fit within the canteen neck and having a diaphragm inward from its outer end and provided with a hole for the passage of the mouthpiece tube, a filter secured to the inner end of the mouthpiece tube, a draft tube extending from the filter, and a helical spring surrounding the mouthpiece tube and acting to project the mouthpiece.

6. A filter for a canteen comprising a filtering chamber adapted to be passed through the canteen mouth, a tube extending from each end of the said chamber, a base having a rim adapted to fit between the neck and the cap of the canteen and also having a hole through which passes one of the tubes extending from the filtering chamber, and a spring acting to project said tube beyond the canteen mouth.

Signed at Seattle, Washington, this 30th day of October, 1918.

TATSUJIRO IMAIZUMI.
